UNITED STATES PATENT OFFICE

FRANK S. BARKS, OF ST. LOUIS, MISSOURI

DISPENSING APPARATUS

Application filed May 8, 1929. Serial No. 361,271.

This invention relates to dispensing apparatus, and with regard to certain more specific features, to guns for grease or the like pumped from automatic pressure pumps or lubricators.

- Among the several objects of the invention may be noted the provision of an improvement in the material gun described in my patent for lubricating apparatus, No. 1,633,504, dated June 21, 1927; the provision of a gun of the class described in which disconnection of certain delivery lines therewith is better facilitated under all operating conditions; and the provision of a simplified form of gun of the class described in which leakage is at a minimum and wherein easier operation and better control are had. Other objects will be in part obvious and in part pointed out hereinafter.
- 20 The invention accordingly comprises the elements and combinations of elements, features of construction, and arrangements of parts which will be exemplified in the structure hereinafter described, and the scope of 25 the application of which will be indicated in the following claim.

In the accompanying drawings, in which is illustrated one of various possible embodiments of the invention,

- 30 Fig. 1 is a side elevation showing the grease gun connected with certain lubricating apparatus; and,

Fig. 2 is a longitudinal section taken through the grease gun per se, showing its connection with a bearing.

Similar reference characters indicate corresponding parts throughout the several views of the drawings.

- 40 Hereinafter a grease gun will be referred to by way of example, but it is to be understood that the device described may be used in connection with other liquid or viscous materials such as putty and the like.

45 Referring now more particularly to Fig. 1, there is illustrated at numeral 1 a grease pumping unit comprising a base 3 on which is supported a driving engine 5 suitably connected with a pump 7 for forcing grease from a supply chamber 9 to an outlet 11. 50 This entire pumping unit has been described

in detail in my said Patent No. 1,633,304 and it is to be understood that the patent may be referred to in connection with the present description.

In the present embodiment the engine 5 is 55 operated by compressed air, as described in said patent, but it is to be understood that by suitable modifications other motive agents may be used, such as electricity. Regardless of the motive agent used, the function of the 60 pumping unit 1 is automatically to provide grease or the like under pressure in an outlet line 13. It is a further function of this device that when the grease gun 15 (to be described), which functions as a valve in this 65 line 13, is closed, then the pressure in said line 13 is maintained. Under these conditions the driving engine 5 (or motor) is not operating. When the grease gun is opened, 70 then the pressure in the line 13 is insipiently relieved and this action automatically causes the engine 5 to start and pump grease under pressure out through the open gun by way of the line 13. The above description 75 is given in order to make clear the point that the gun to be described is used in connection with a device which automatically starts operating to pump material when the gun is open and automatically stops pumping when the gun is closed.

80 Referring now more particularly to Fig. 2, the gun 15 per se will be seen to comprise a body 17 having a longitudinal differential bore 19, this bore being provided with a plunger 21. The plunger 21 is, with a 85 leather sealing piston 23, fastened to a stem 25 which is slidable in a section 27 of said bore, said stem emerging therefrom.

At its upper portion, the bore 19 is intersected by a laterally formed communicating 90 passage 29, the plunger 21 crossing the passage. Below the passage the plunger 21 is provided with a nose 31 adapted to press a ball check valve 33 from its seat 35. The 95 portion of the bore 29 around the nose 31 is large enough to permit passage of grease and like fluids therethrough. A spring 47 reacting against an inlet nipple 49 normally holds the ball valve 33 to its seat. It will 100

be noted that the nipple 49 comprises a free inlet.

The stem 25 is adapted to be pressed down by means of an adjustable pin 37, the latter being locked to a handle 39. The handle is pivoted to links 41 which in turn are pivoted to said body 17. A downwardly extending slotted lug 43 of the handle 39 is adapted to engage the head of a limiting stop pin 45, so that the plunger 21 and its supporting stem 25 cannot leave the hollow body 17. If it is desirable to open the check valve 33, the handle 39 may be depressed, whereupon the nose 31 unseats the valve. Thus the inlet and outlet of the body communicate with one another and with the lateral passage 29.

Screwed sidewardly into the intersecting passage 29 is a pressure reducing cylinder 51 provided with a communicating bore 53 and a rearward threaded cap 55. The cap 55 is provided with a cooperating threaded stem 57 which carries an operating handle 59 and has a relatively flat forward face 61 for engaging a plug 63 which rides in an enlargement of the bore 53 and is sealed by means of a leather piston ring 65. The threaded stem 57 and plug 63 are not rigidly connected. Hence the free piston 63, 65 may be given translatory motion without rotation when the stem 57 is turned from the handle 59 and thus scoring and tearing of the leather ring is reduced.

The outlet of the passage 29 is threaded to receive the threaded end of the flexible outlet tube assembly 14, the latter being provided with a bayonet slotted head 67 such as is used for connecting assemblies of this type to oiling tips. A tip is illustrated at numeral 69 screwed into a device to be greased, such as the bearing 71. The function of the tip 69 is that of a check valve permitting flow of material from the line 14 but not back into the same. A knurled portion or the like, such as 73, is usually provided for manual application to, and removal from the tip 69 of the head 67. The operation for greasing comprises pushing the head 67 over its tip 69 and then twisting the head 67, whereupon if pressure is built up in the line 14, then it is almost impossible to manually remove the head 67 until the pressure is relieved.

With the ordinary grease guns it is particularly difficult to release this pressure if a clogged bearing is encountered, especially where guns such as the one shown in my Patent 1,633,304 include a booster arrangement which permits a building up of the pressure beyond that supplied by the pump shown in Fig. 1. With this increased pressure it is sometimes possible to open an otherwise clogged bearing, but not always.

However, in many cases the pressure of the pump itself is enough to open the bear-

ing and the booster arrangement is superfluous. Under any conditions however, a bearing will be found from time to time which will not yield to the pump pressure and yet it is not desired to use certain necessarily extra parts on the gun required to render the booster effective, merely for the scattered cases of extraordinary clogging. The extra parts referred to are those such as shown by numerals 179 and 183 to 189 in said Patent 1,633,304. These parts it will be seen to be advantageous to eliminate.

The elimination of the parts above referred to not only results in mechanical simplification but also in a new function which will be clear from the following: A grease gun has for its purpose the closing and opening of the grease passage, whereby pumping by the engine 5 is prevented, or permitted to take place, as desired. If the line 13 is positively closed at the gun, the engine 5 ceases to operate. If the line is opened grease can pass and the air engine automatically goes into operation and continues so until the line is again closed.

After a bearing has been sufficiently greased, the grip on the handle 39 which opened the gun is released, whereupon the ball check valve 33 closes under action of the spring 47 and the pressure there-behind. If the bearing was not clogged, then the pressure on the outlet line 14 automatically decreases after closure of the valve 33. This permits ready removal of the head 67.

If, after closure of the valve 33, it should be discovered that the head 67 can not be removed from its tip because of its clogged bearing not permitting release of pressure, then the handle 59 can be backed up so as to increase the volume available into which the grease may expand. This will result in reduction of the pressure so that the head 67 can be easily removed. The checking action of the valve 33 prevents the pump 1 from automatically pumping into the line 14 when pressure is reduced by means of the handle 59.

While the gun of Patent 1,633,304 can provide the pressure reducing result under certain circumstances, yet it does not do so under all circumstances. For instance, referring to Fig. 2 herein, if the stem 57 has previously been retracted so far so that the piston 63, 65 rested against the cap 55, then if the pump builds up pressure against a clogged bearing, this pressure can not be reduced by further unscrewing the stem 57. This condition often occurs, due to an operator forgetting to screw in the stem 57 prior to opening the valve. With the device of Patent 1,633,304, under these conditions, the operator would attempt to boost the pressure by screwing in the stem. If, as might occur, the booster pressure would not open the bearing it would be necessary

to uncouple the head from the greasing tip with a wrench with consequent danger of breakage and loss of time.

By means of the present invention, which eliminates the inlet check valve at the nipple 49, the operator cannot get into such a predicament. This is because if he has turned on the pump against an unopenable bearing with the piston 63, 65 retracted 10 as far as it will go, he needs, upon closing the valve 33, merely screw in the stem 57 so as to drive the piston 63, 65 down the bore 53. Hence the check valve 33 is opened and grease is driven back into the line 13 15 to its source. Then, upon backing off the stem 57, the check valve 33 closes and the volume in communication with the bearing is decreased so as to decrease the pressure in the line 14. Thus ready removal of the 20 head 67 can be effected under any and all circumstances.

In view of the above, it will be seen that the several objects of the invention are achieved and other advantageous results 25 attained.

As many changes could be made in carrying out the above constructions without departing from the scope of the invention, it is intended that all matter contained in 30 the above description or shown in the accompanying drawings shall be interpreted as illustrative and not in a limiting sense.

I claim:

Dispensing apparatus comprising a body, 35 an inlet therefor, a check valve normally preventing flow from the inlet to the body, an outlet from the body communicating with the inlet by means of said check valve and adapted to receive material therefrom, 40 means communicating with the outlet adapted to decrease pressure thereat and independent manually operable means for opening said check valve to permit flow from the inlet to the outlet, said pressure 45 decreasing means being adapted to force material through said check valve to the inlet should the outlet be clogged.

In testimony whereof, I have signed my name to this specification this fourth day 50 of May, 1929.

FRANK S. BARKS.
